GEARED TURBINE INSTALLATION

Ernest Henry Buchanan Anderson, Westfield, N. J., assignor to Charles Algernon Parsons, Newcastle-on-Tyne, England; Katharine Parsons, Vincent Thompson, and Frederick Gordon Hay Bedford, legal representatives of said Charles Algernon Parsons, deceased

Application July 9, 1929, Serial No. 376,943, and in Great Britain July 17, 1928

5 Claims. (Cl. 74—56)

The invention relates to geared turbine installations of the type in which a number of turbines drive pinions gearing with a common wheel.

A main object of the present invention is to improve the structural features of such an installation with a view to facilitating overhaul or replacement of parts.

With this and other objects:

The invention consists in a casing for a geared turbine installation of the kind indicated having a plurality of turbines, and preferably for such an installation in which the axes of two of the turbines are situated in a plane passing through the axis of the main gear wheel, the axis or axes 15 of the other turbine or turbines being situated at a higher level and in the case of two turbines preferably in a plane parallel to the first-mentioned plane.

The invention also consists in the improved 20 turbine installations and certain structural details thereof to be hereinafter described or indicated.

Referring to the accompanying diagrammatic drawings, which show one form of the invention 25 by way of example:—

Figure 1 shows a plan view of a two-plane four-pinion geared turbine installation with the casing cover removed,

Figure 2 being a corresponding side elevation of the casing,

Figure 3 shows an end view of the casing looking aft,

Figure 4 being a section on the line 4—4 of Figure 3,

Figure 5 shows a section on the line 5—5—5—5 of Figure 6, while

Figures 6 and 7 are sections respectively on the lines 6—6 and 7—7 of Figure 5.

The same reference symbols are used in the 40 different figures to denote corresponding parts.

In carrying the invention into effect according to the illustrative form shown, applied by way of example to a marine turbine installation, the shafts of a high pressure, first intermediate 45 pressure, second intermediate pressure, and low pressure turbine, A, B, C, D, hereinafter referred to respectively as H. P., I. P., first I. P., second I. P. and L. P. turbines, are coupled respectively to pinion shafts a, b, c, and d, each having formed 50 integrally therewith a pinion gearing with a common gear wheel mounted on the propeller shaft, f, and consisting of two helical wheels, e¹, e², one right-hand and one left-hand spaced apart, each pinion being also divided into right-hand and left-hand sections, a¹, a², b¹, b², c¹, c²

and d¹, d², spaced apart to mesh respectively therewith. In this way, as hereinafter described, each pinion shaft may be provided with three bearings, a³, a⁴, a⁵, b³, b⁴, b⁵, and so forth, one between the two pinion sections and the others 60 outside the right-hand and left-hand pinions respectively.

Of the four turbines, the axes of the L. P. and 1st I. P., D and B, lie in the horizontal plane passing through the axis of the main gear wheel, 65 symmetrically one on each side of the axial vertical plane therethrough, while the axes of the H. P. turbine, A, and the 2nd I. P. turbine, C, lie in a parallel plane above the axis of the main gear wheel and similarly one on each side of the 70 axial vertical plane.

In addition, the H. P. turbine, A, and the 1st I. P. turbine, B, are arranged on the forward side of the main gear wheel while the 2nd I. P. and L. P. turbines, C and D, are arranged on the 75 after side of the main gear wheel.

With this arrangement, it will be seen that the two turbines on the forward side and the two turbines on the after side of the main gear wheel are respectively at different levels so that the 80 upper one of each pair can drain by gravity into the lower one.

The L. P. turbine, D, may be of the double-flow type and embody in its structure the L. P. section, D¹, of an astern turbine, the corresponding H. P. 85 section, C¹, of the astern turbine being associated with the 2nd I. P. turbine, C.

As regards the structural features of such an installation, the casing or housing of the gear wheels comprises a lower base portion, h, of a 90 hollow quadrangular form as seen in plan extending upwardly to the horizontal plane passing through the axis of the main gear wheel and provided with bearings, e³, e⁴, therefor and also bearings b³, b⁴, b⁵ and d³, d⁴, d⁵, for the pinion 95 shafts, b, d, of the 1st I. P. and L. P. turbines, B and D, these bearings being arranged respectively in the end walls, h¹, h², and on brackets, h³, inwardly projecting from the longitudinal walls of the quadrangle into the space between the two 100 sections, e¹, e², of the main gear wheel.

All the bearings are provided with suitable caps.

To support the pinion shafts, a, c, situated in the second plane, the upper part of the gear casing is formed as a girder structure extending upwardly from the top of the base portion, h¹, to which it is attached by any convenient means, and arching over the main gear wheels. This girder structure comprises end walls, h⁴, h⁵, a hollow transverse wall, h⁶, partly supported by the 110

brackets, h^3 , and situated between the two sections of the gear wheel, e^1 , e^2 , and a shell, h^7 , the top of which is provided with bearings, a^3 , a^4 , a^5 and c^3 , c^4 , c^5 , for the pinion shafts, a and c , of the

5 H. P. and 2nd I. P. turbines, A and C, respectively.

As before, three bearings are provided for each such pinion with suitable caps to hold the pinion shafts in place.

10 The girder structure described is conveniently constructed in two parts bolted together in a vertical plane passing through the axis of the shaft, f .

15 In order to provide for overhaul or replacement of the 1st I. P. and L. P. pinion shafts, b and d , the central transverse girder, h^6 , of the upper part of the casing structure is provided with arched recesses, h^8 , into which the caps or pinion shafts, b , d , themselves may be raised for withdrawal, access being obtained to these parts by 20 apertures, h^9 , through the casing wall, h^7 , fitted with detachable covers, h^{10} . With a similar object, apertures, h^{11} , corresponding to such recesses are also provided in the end walls, h^4 , h^5 , and are fitted with detachable plates, h^{12} , with which may 25 be embodied the upper halves, h^{13} , of the pinion-shaft housings and it may be also the facings, h^{14} , or parts of them, hereinafter described for the attachment of the relative turbines.

30 Similar detachable plates and adjuncts are preferably fitted in respect of the shaft, f .

Finally, a detachable cover, h^{15} , is provided to 35 enclose the six bearings, three for the H. P. and three for the 2nd I. P. pinion shafts carried on the top of the casing, facings, h^{14} , being similarly provided for the attachment of the H. P. and 2nd I. P. turbines.

40 The structure described is ribbed and stiffened as required to give it the necessary strength and in addition is provided with facings, h^{14} , on its two end walls for the attachment of the relative turbines, the whole power unit thus being embodied in a single rigid structure.

45 Further, the quadrangular base portion of the frame is supported on stiffened seatings, i , i , in the ship's structure and is preferably enclosed below, for example by a light trough, k , or the like of sheet metal.

50 With a structure as described, the machine work and boring out of the different bearings is readily accomplished by ordinary workshop methods while easy access is afforded to all the pinion shafts for inspection and overhaul.

55 The same general arrangement may be used either with pinions of the same size or with pinions of different size to provide for different speeds of running of the various turbine sections.

60 Alternatively, instead of the preferred arrangement of double-helical teeth as described, the same set of turbines may be used in connection with single helical teeth, the thrust reactions being taken up by the turbine blading, by dummy pistons or otherwise.

Finally, a casing as described may be readily modified to provide for the case of a three-pinion installation in which only one pinion shaft is arranged in the upper plane.

65 It will be seen that other arrangements of the different turbine sections may be used and the structural details of the gear casing may be varied without exceeding the scope of the invention as defined in the claims appendant hereto.

Having now described my invention, what I claim as new and desire to secure by Letters Patent is:

1. A turbine gear casing comprising a base portion provided with bearings for the main gear wheel shaft and for two turbine pinion shafts substantially in the same horizontal plane with the main gear wheel shaft, and a detachable upper portion provided with bearings for at least one turbine pinion shaft, said upper portion including end walls and a transverse hollow wall provided with recesses into which the lower pinion shafts may be raised for endwise withdrawal of the pinion shafts.

2. A turbine gear casing as claimed in claim 1, in which the detachable upper portion consists of an intermediate casing element providing the lower bearings for the upper pinion shafts and a top cap forming a third casing element and providing upper bearings for the upper pinion shafts.

3. A turbine gear casing comprising a quadrangular base portion having interior brackets and provided with bearings for the main gear wheel shaft and two turbine pinion shafts, and a detachable upper portion provided with bearings for at least one turbine pinion shaft and having 110 end walls, a shell, and an intermediate hollow transverse wall supported by said brackets.

4. A turbine gear casing comprising a base portion provided with bearings for the main gear wheel shaft and two turbine pinion shafts, and a 115 detachable upper portion provided with bearings for at least one turbine pinion shaft and having end walls, a shell and an intermediate hollow transverse wall, said end walls and transverse wall being provided with recesses into which the lower 120 pinion shafts may be raised for endwise withdrawal, and detachable plates in said recesses forming the upper halves of the bearings for the lower turbine shafts.

5. A turbine gear casing comprising a lower 125 portion, a removable upper portion, bearings on the lower portion adapted to support a gear wheel formed of elements spaced apart, bearings arranged to extend outside of and between the elements and adapted to support pinions formed 130 of elements spaced apart, and an intermediate hollow transverse wall carried by the upper portion of the casing and arranged to extend between the two elements of the main gear wheel, said transverse wall carrying the intermediate 135 bearings for the pinion shafts.

ERNEST H. B. ANDERSON.
